UNITED STATES PATENT OFFICE.

MAX PEINLICH, OF WHITE PLAINS, NEW YORK, ASSIGNOR TO MILLERS' BRASS FITTING CO. INC., A CORPORATION OF NEW YORK.

DESIGN FOR A LIGHTING-FIXTURE ARM.

Application filed November 26, 1924. Serial No. 11,496. Term of patent 3½ years.

To all whom it may concern:

Be it known that I, MAX PEINLICH, a citizen of the United States of America, and a resident of White Plains, in the county of Westchester and State of New York, have invented a new, original, and ornamental Design for Lighting-Fixture Arm, of which the following is a specification, reference being had to the accompanying drawing, forming a part thereof.

In these drawings:

Fig. 1 shows an inverted plan view of the lighting fixture arm, and

Fig. 2 shows a diagrammatic outline in side elevation of the lighting fixture arm.

I claim:

The ornamental design for a lighting fixture arm substantially as shown.

MAX PEINLICH.
